UNITED STATES PATENT OFFICE.

LOUIS V. JOHNSON, OF FORT WORTH, TEXAS.

DEVICE FOR BORING ENGINE CYLINDERS.

1,406,871.

Specification of Letters Patent. Patented Feb. 14, 1922.

Application filed July 24, 1920. Serial No. 398,631.

To all whom it may concern:

Be it known that I, LOUIS V. JOHNSON, a citizen of the United States, residing at Fort Worth, in the county of Tarrant and State of Texas, have invented certain new and useful Improvements in Devices for Boring Engine Cylinders, of which the following is a specification.

This invention relates to devices for boring engine cylinders and more particularly to a device for boring the cylinders of rotary engines of the type disclosed in my co-pending application filed July 6, 1920, Serial No. 394,216. In engines of this type embodying a rotor having radially shiftable or movable blades, which rotor is mounted eccentrically within the engine cylinder, the inner surface of the wall of the cylinder does not describe a true cylindrical form but is of necessity of an irregular shape, diametrically opposite portions of the wall being eccentric to the true axis of the cylinder whereas the intervening diametrically opposite portions of the wall are concentric to the said axis. It is my understanding that great difficulty has been experienced in boring cylinders for engines of this type, and the primary object of the present invention is therefore to provide a boring device which may be conveniently employed in any of the ordinary forms of lathes, for the purpose of accurately, readily, and expeditiously boring cylinders of this type.

Another object of the invention is to so mount and construct the cutter and the support therefor, in a device for this purpose, that, in the operation of the device, the work being acted upon will in a sense constitute a templet, and a portion of the support for the cutting tool will coat therewith in such a manner as to insure of correct and accurate cutting of the cylinder wall.

In the accompanying drawing:

Figure 1 is a vertical transverse sectional view illustrating the device embodying the present invention in operation in boring a cylinder of the type above mentioned;

Figure 2 is a horizontal sectional view through the structure taken substantially on the line 2—2 of Figure 1;

Figure 3 is a detail transverse sectional view on the line 3—3 of Figure 1;

Figure 4 is a perspective view illustrating one of the members of the device.

In the drawing, the numeral 1 indicates the work which is an engine cylinder of the

type heretofore mentioned, and in Figure 1 of the drawings this piece of work is illustrated as disposed upon the adjustable bed 2 of any of the well-known types of lathes or boring machines, the work being preferably held in place by a band 3 disposed about the outer side of the cylinder and having threaded ends 4 which may be fitted through openings in the bed 2 and which may have bolts 5 applied thereto for the purpose of tightening the band. In Figure 2 the numeral 6 indicates the face plate of the lathe or boring machine and 7 the usual center associated therewith. The numeral 8 indicates the center which is carried by the lathe carriage, and disposed between the centers 7 and 8 is a short shaft which is indicated by the numeral 9. The numeral 10 indicates a dog which is clamped to one end of the shaft 9 and which is engaged with the face plate 6 so as to provide for rotation of the shaft 9 with the said plate in the operation of the machine. The shaft 9 extends through the work 1 and carries and forms a part of the device embodying the invention.

In addition to the shaft 9, the device embodying the invention comprises a pair of counterpart cheek members indicated in general by the numeral 11 which members are of circular form and provided with hub portions 12 keyed or otherwise secured, as at 13, upon the said shaft 9, the said members being secured together by means of bolts 14 and when assembled constituting the head of the device. The cheek pieces 11 are formed in their inner faces with recesses 15 which extend diametrically of the said faces of the members and which terminate at their ends in slots 16 which open at their outer ends through the peripheries of the respective cheek members. When the members are assembled these recesses and slots register, as will be evident by reference to Figure 2 of the drawings.

The tool holder of the device is indicated in general by the numeral 17 and the said holder comprises a yoke 18 which is disposed slidably within the housing provided by the matching recesses 15 and which straddle the shaft 9. This yoke 18 is provided at its opposite ends with shank portions which are indicated one by the numeral 19 and the other by the numeral 20, these portions projecting through the slots 16 in the manner clearly shown in Figure 1 of the drawing. The shank 19 is formed

with a longitudinally extending socket 21 in which is seated the tang of the tool indicated by the numeral 22. In order that the tool may be adjusted to project a greater or less distance at its cutting end beyond the end of the shank 19, an adjusting screw 23 is threaded through the inner end wall of the socket 21 and bears against the end of the tool tang 22, this adjusting screw being provided with any suitable kind of head 24 whereby it may be rotated, and the shank 19 being formed with a transverse opening or passage 25 receiving this head and permitting of access thereto. In order that the tool may be secured in its positions of adjustment, a set screw 26 is threaded through the outer end portion of the shank 19 and bears at its inner end against the upper side of the said tool.

20 The shank 20 of the tool holder 17 is preferably reduced upon its upper and under sides as indicated by the numeral 27, and fitted thereto is a nose piece indicated in general by the numeral 28. This nose piece comprises base portions 28 and a connecting portion 30 which is rounded at its outer end to form the nose. The nose piece is disposed with its base portions straddling the reduced end of the shank 20 and may 25 therefore be adjusted longitudinally of the said portion of the shank. In order that the nose piece may be held in positions of adjustment, a set screw 31 is threaded to one of the base portions 29 and bears against 30 the adjacent side of the reduced portion of the shank.

The shaft 9 is formed with a recess 31' which extends radially therein, and disposed to seat at one end within this recess 40 is a coil spring indicated by the numeral 32, the spring bearing at its other end against the adjacent end wall of the opening in the yoke 18 or more specifically that wall which is located next adjacent the 45 shank 20. The tendency of this spring is to yieldably hold the tool holder in a direction to retract the tool, and consequently movement of the tool holder in a direction to project the tool must be against the tension of this spring.

As previously stated, the device embodying the invention is designed for the purpose of boring the cylinders of engines of that type embodying a rotor having diametrically shiftable or slidable pistons and in which the rotor is mounted eccentrically within the chamber or bore of the cylinder, and from the preceding description it will be evident that the device of the invention 55 operates somewhat in the manner of the rotor of such an engine. For example after it has been determined what position the axis of the rotor of the engine shall have with respect to the axis of the engine cylinder, the method of procedure in boring the

cylinder block is as follows: The block is first formed with a cylindrical bore of predetermined dimensions, and is then secured upon the bed 2 of the boring machine. The device embodying the invention is then adjusted to working position and in this adjustment the axis of the shaft 9 is brought to identically the same position with relation to the true axis of the cylinder as initially bored, as it is intended the axis of the rotor of the engine shall bear to the axis of the engine cylinder. Then when the shaft is rotated, the tool 22 will be caused to operate within the cylindrical bore initially formed in the cylindrical block, and the blade may 70 be adjusted in an outward direction from time to time as required. Due to the eccentric location to the axis of the shaft 9 with relation to the true axis of the cylinder, the 75 nose 30 will continuously contact the wall of the cylinder bore and as it rides over the portion of the wall of the bore which is nearer the axis of the shaft 9, will be forced in a radial direction thus projecting the cutter 22 to a greater or less distance. Thus 80 when the tool holder 17 is in the position shown in full lines in Figure 3 of the drawings, the nose 30 will ride against a portion of the wall of the cylindrical bore and as 85 the nose and the tool, in this position of the parts, extend on a line below the true axis of the cylinder bore, the bit of the tool will be caused to cut into the wall of the cylinder at a point chordally opposite the point engaged by the said nose. However 90 as the parts reach the dotted line position shown in the said figure, and before and immediately after they reach this position, the distance between the nose 30 and the bit 95 of the tool 22 will be less than the diameter of the cylindrical bore and as these elements will then be on a line extending substantially diametrically through the axis of the said cylindrical bore, the cutting end or bite of the tool will clear the wall. The device 100 embodying the invention will of course be more or less continuously rotated, and the cutting tool 22 will be adjusted from time to time until finally the wall of the bore 105 will have been brought to the required irregular curvilinear contour.

Having thus described the invention, what is claimed as new is:

1. In a device of the class described, a rotatable shaft, a head fixed upon the shaft 120 for rotation therewith and interiorly chambered and provided at its periphery with oppositely located openings communicating with the chamber, a yoke shiftably mounted in the chamber and transversely of the 125 shaft, a shank extending from one end of the yoke and through one of the said openings for the support of a cutting tool, a shank extending from the other end of the yoke and through the other opening, and 130

a nose carried by the last-mentioned shank, the walls of the openings in the head supporting and steadyng the shanks of the yoke relatively close to their outer ends whereby 5 to prevent chattering of the tool.

2. In a device of the class described, a rotatable shaft, a head fixed upon the shaft for rotation therewith and interiorly chambered and provided at its periphery with 10 positively located openings communicating with the chamber, a yoke shiftably mounted in the chamber and transversely of the shaft, a shank extending from one end of the yoke and through one of the said open-

ings for the support of a cutting tool, a shank extending from the other opening, a nose carried by the last-mentioned shank the walls of the openings in the head supporting and steadyng the shanks of the yoke relatively close to their outer ends whereby 15 to prevent chattering of the tool, the shaft being recessed, and a spring seated at one end within the recess in the shaft and bearing at its other end against the inner side of that end of the yoke from which the last- 20 mentioned shank extends.

In testimony whereof I affix my signature.

LOUIS V. JOHNSON. [L. s.]
